(57) CLAIM

The ornamental design for a pedestal barbecue, as shown and described.

DESCRIPTION

FIG. 1 is an upper front side perspective view of the pedestal barbecue showing my new design;

FIG. 2 is a front elevational view thereof;

FIG. 3 is a right side elevational view thereof;

FIG. 4 is a top plan view thereof;

FIG. 5 is an upper front perspective view thereof with the lid in an open position;

FIG. 6 is a right side elevational view of FIG. 5;

FIG. 7 is a front elevational view of FIG. 5; and,

FIG. 8 is a top plan view of FIG. 5.

The rear portion of the barbecue and portions of the grill in FIG. 8 which are not shown in the drawings or described in the specification form no part of the claimed design.
